200,007

SPOON OR SIMILAR ARTICLE

Martin Schnur, West Orange, and Mel Appel, Murray Hill, N.J., assignors to Dake Plastics, Inc., Elizabeth, N.J.

Filed May 3, 1963, Ser. No. 74,734

Term of patent 14 years

(Cl. D54—12)

FIG. 1

FIG. 2

FIG. 3

FIG. 4

FIG. 5

FIGURE 1 is a front elevational view of a spoon showing our new design;

FIGURE 2 is a rear elevational view thereof;

FIGURE 3 is a side elevational view thereof;

FIGURE 4 is a front end view thereof;

FIGURE 5 is a rear end view thereof;

The dominant features of our design reside in the particular handle portion as shown. The design is intended for use on sets comprising forks, spoons, knives and similar articles of flatware.

We claim:

The ornamental design for a spoon or similar article, as shown and described.
